US0D1002112S

(12) **United States Design Patent** (10) **Patent No.:** **US D1,002,112 S**
(45) **Date of Patent:** **** Oct. 17, 2023**

(54) **DENTAL APPLIANCE**

(71) Applicant: **SHANGHAI SMARTEE DENTI-TECHNOLOGY CO., LTD.**,
Shanghai (CN)

(72) Inventors: **Xingxing Wang**, Shanghai (CN);
Huimin Zhuang, Shanghai (CN);
Junfeng Yao, Shanghai (CN)

(73) Assignee: **SHANGHAI SMARTEE DENTI-TECHNOLOGY CO., LTD.**,
Shanghai (CN)

(**) Term: **15 Years**

(21) Appl. No.: **29/792,288**

(22) Filed: **Mar. 18, 2022**

(30) **Foreign Application Priority Data**

Dec. 31, 2021 (CN) 202130880699.6

(51) LOC (14) Cl. **24-03**

(52) U.S. Cl.

USPC **D24/181; D29/108**

Primary Examiner — Elizabeth J Oswecki

(57) **CLAIM**

The ornamental design for a dental appliance, as shown and described.

DESCRIPTION

FIG. 1 is a perspective view of a dental appliance showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 8 Drawing Sheets
